WAVE TRANSLATING DEVICE

Alexander I. Abrahams, New York, N. Y.

Application April 28, 1933, Serial No. 668,335

6 Claims. (Cl. 179—138)

This invention relates to wave translating devices, and with particularity to a device for translating sound waves into electric waves and vice versa.

5 The invention has for its principal object to provide an improved form of wave translating device employing a ribbon like vibratory translating element.

A feature of the invention relates to an improved type of microphone.

A further feature relates to an improved form of wave vibratory element suitable for use in wave translating devices such as microphones, reproducers or the like.

15 A still further feature relates to the novel organization, arrangement and relative location of parts which go to make up a simple and highly efficient wave translating device.

Other features and advantages not specifically 20 enumerated will be apparent after a consideration of the following detail descriptions and the appended claims.

Referring to the drawing,

Fig. 1 is a front view of a device according 25 to the invention;

Fig. 2 is a right hand elevational view, partly 30 in section of the device of Fig. 1;

Fig. 3 is a partial top plan view of the device 35 of Fig. 1 with the cover and housing removed;

30 Fig. 4 is a partial sectional view of Fig. 2 taken along the line 4—4 thereof;

Fig. 5 is a sectional view of Fig. 3 taken along the line 5—5 thereof; and

35 Figs. 6 and 7 show modified forms of ribs formed in the vibratory member.

Referring more particularly to the drawing there is shown a rectangular frame member 1 having flanges 2 and 3. Each of the flanges 2 and 3 is provided with a recess 4 to receive an insulating strip 5. The strips 5 are attached to the flanges 2 and 3 by suitable screws 6. Mounted on each of the insulator strips 5 is a metallic strip 7 which is fastened thereto by means of screws 8. The metallic strips 7 serve to clamp 40 the ends of the vibratory member 9 against the associated insulator members 5. As shown in the drawing, the member 9 is preferably in the form of a metallic ribbon of thin material such as aluminum, duralumin or the like. In order

45 to stiffen the member 9 longitudinally to enable it to vibrate in a piston like manner the said strip is provided with a longitudinal embossed rib 10. To further facilitate the vibration of the member 9 in a piston like manner the ends 50 of said member may be provided with transverse embossings 11. While the drawing shows the member 10 consisting of a single recess, it will be understood that the invention contemplates the provision of a series of separate longitudinal recesses as desired. It is of course apparent that

5 the rib 10 need not be straight but can have other configurations as shown at 10^a and 10^b in Figs. 6 and 7. Similarly, while the drawing shows a single transverse recess, at each end of the ribbon member, it will be understood that a plurality of these ribs may be provided at each end to increase the flexibility of the said member, as shown in Fig. 6. In addition the transverse ribs whether used singly or in multiple may extend to the edges of member 9 as shown in Figs. 6 and 10 10 at 11^a.

15 It will also be understood that other well known expedients for rendering the ends of the ribbon flexible may be employed. If desired the member 9 may have its opposite ends clamped between the members 5 and 7, so as to maintain the said member 9 in a state of tension, although this is not absolutely necessary so long as the said member 9 is actively moving throughout the greater portion of its length in a piston like 20 manner, that is with its substantial entire area moving uniformly for a given unit of force impressed thereon. For the purpose of conducting current through the member 9 there is provided a lead-in wire 12 which is fastened by means of 25 screw 8 and therefore contacts with the lower end of the member 9. Another lead-in wire 13 connects with the upper end of the member 9. By means of these wires 12 and 13 therefore 30 external connections can be made to the ribbon member 9.

35 Attached to the front face of the member 1 are a pair of pole pieces 14, 15. As shown more clearly in Figs. 2 and 4 these pole pieces are in the form of flat metal members of iron or other magnetic material, and are held in place by means of screws 16 so as to define a longitudinal magnetic gap between their opposed edges, in which gap is situated the member 9. It will be understood of course that the member 1 carrying the pole pieces 14 and 15 is of non-magnetic 40 material such as aluminum or the like.

45 As will be apparent from the drawing the gap defined by the pole pieces is slightly wider than the width of the member 9 so as to enable the said member 9 to vibrate without contacting with the surface of the poles. Situated in the rear of the member 9 is a rigid strip 17 of non-magnetic material such as brass or the like. The strip 17 is carried by a pair of screws 18 and 19 which are threaded into the flange portions 2 of the member 1. By means of the screws 18 therefore the clearance or spacing between the member 9 and the member 17 may be accurately 50 adjusted for purposes hereinbelow described.

55 The magnetic energization of the pole pieces 14 and 15 may be achieved in any well known manner, for example there is shown in the drawing a pair of U-shaped magnets 20 and 21 which engage the pole pieces 14 and 15, as shown clear- 60

ly in Fig. 4. The magnets 20 and 21 may be held firmly in position by means of screws 22 passing through the wall of the member 1. Preferably, although not necessarily, the space defined by 5 the U-shaped magnets is provided with a filling of a non-resonant material such as cotton, wool or the like, as indicated by the numeral 23. As will be apparent from Fig. 4, the damping plate 17 is of slightly less width than the member 9 10 so as to allow egress of air from the back of the member 9 into the space defined by the magnets. However, because of the filling material 23 the air in this space is prevented from resonating at any frequency within the useful range of 15 the device.

For the purpose of enclosing the above assembly there is provided a cylindrical cup shaped housing 24 of metal or other suitable material having a threaded flange 25 to receive a correspondingly threaded cap member 26. The cap member 26 is provided with a series of four locks 27 which engage the respective corners 28 of the member 1 to clamp the above described assembly firmly in position between the cap and the flange 25. If desired the annular opening in the cap 26 may be provided with a covering of foraminous material such as ordinarily employed in microphones or the like, for the purpose of allowing the sounds or other waves to impinge 30 upon the member 9 while protecting said member against mechanical injury, dust and the like.

When the device described above is to be used as a microphone the sounds or other waves to be translated into corresponding currents impinge 35 upon the member 9, causing it to vibrate throughout its effective length. Since this member is situated in an intense and concentrated magnetic field defined by the pole pieces 14 and 15, there are generated currents corresponding to 40 the waves affecting the member 9. These currents may be taken off by means of the lead wires 12 and 13 and connected to suitable amplifying and/or current transmitting devices. On the other hand, when the device is to be used 45 as a sound reproducer the sound currents are applied to the lead-wires 12 and 13 causing corresponding electric fields to be set up in and around the member 9, and resulting in corresponding vibrations of this member.

It has been found that by means of the damping plate 17 the response of the device may be 50 varied as desired. For example the elastic restoring force of the vibratory system is a function of the area of the member 17 and its spacing relative to the member 9. Secondly, by varying 55 this latter spacing the inherent restoring force of the system, and consequently the resistance thereof may be accurately varied.

It will be understood of course that the invention is not limited to the use of this air damping 60 to control the response of the device. For example, the member 9 may be subjected to any desired tension so as to control its actual period of vibration. However, as above described preferably the member 9 is designed and maintained 65 so as to vibrate in a substantially piston like manner. The restoring forces or elasticity of the vibrating system being substantially entirely provided by the air space between the member 9 and the member 17. It is to be noted that since 70 the member 17 is of less width than the vibratory member 9 the impinging sound waves strike the

latter member directly, and there is no reflection of sound from the member 17 towards the front of the device, the release of air in back of the member 9 being effected by the space between the longitudinal edges of the member 17 and the 5 pole pieces as indicated by the arrows in Fig. 4. However, because of the packing or filling 23 this release of air does not produce a resonant response in any portion of the useful range of 10 the device.

It will be understood that various changes and modifications may be made herein without departing from the spirit and scope of the invention, and while particular materials have been specified the invention is not limited thereto. 15 For example, the member 9 may be treated or formed to impart to it the necessary or required elasticity and/or rigidity. Likewise, this member instead of being made in the form of a continuous strip may be perforated or otherwise 20 formed to control its actual period of vibration. Likewise, the packing strip 17 may be formed or perforated to control the response of the device, and if desired the member 17 may be adjusted not only to vary the distance between it and the 25 member 9, but also to vary the distance between it and the pole pieces 14 and 15.

It will be understood of course that instead of employing permanent magnets for magnetically energizing the device, any well known form of 30 electromagnets may be employed for this purpose.

What is claimed is:

1. A wave translating device in the form of a ribbon of conductive material, a pair of magnetic poles between which said ribbon is mounted, 35 and a backing plate mounted in spaced relation to said ribbon between said pole pieces.

2. A device according to claim 1, in which the said plate is adjustably mounted with relation to said ribbon member. 40

3. A device according to claim 1, in which the said plate is substantially co-extensive in length with said ribbon, but is of lesser width than said ribbon.

4. A device of the character described comprising a pair of pole pieces defining a magnetic gap in the form of a rectangular slit, a rectangular strip of conductive material mounted in said gap with the edges of the strip in spaced relation to the opposing edges of said pole pieces, 50 a backing strip, and means for adjusting the spacing between said ribbon member and said backing strip.

5. A device according to claim 4 in which the backing strip is substantially co-extensive in 55 length with the ribbon member, but is of lesser width to provide defferent passages for the air in back of said ribbon member.

6. In a device of the character described the combination of a U-shaped magnet, a pair of 60 magnetic plates carried by the poles of said magnet to define a slit-like magnetic gap, a ribbon diaphragm mounted in said gap and insulated from said magnet and pole pieces, current conducting leads connected to opposite ends of said 65 diaphragm, a damping plate mounted in spaced relation to said diaphragm and to said pole pieces, and means for avoiding undesired resonance in the air space in back of said diaphragm and damping plate.
